UNITED STATES PATENT OFFICE.

VINCENT LOMBARDI, OF BROOKLYN, NEW YORK.

KNITTED FABRIC.

1,426,576.

Specification of Letters Patent. Patented Aug. 22, 1922.

Application filed March 26, 1921. Serial No. 455,894.

To all whom it may concern:

Be it known that VINCENT LOMBARDI, a citizen of the United States, residing at Brooklyn, in the county of Kings and State 5 of New York, has invented new and useful Improvements in Knitted Fabrics, of which the following is a specification.

The invention relates to the manufacture of knitted fabrics with the object in view 10 of providing an improved knitted fabric consisting of a plurality of independent, in one part transversely extending yarns, forming interlocking loops in another part and particularly adapted for producing a 15 fabric of peculiar uniformity on both sides thereof, capable of various designs, particularly free from floats so obnoxious in design knitting and of great strength and durability.

20 The drawing illustrates in Fig. 1, diagrammatically a number of adjacent courses of yarn, in Fig. 2, a horizontal cross section on line II-II of Fig. 1, and in Fig. 3, a considerably enlarged fragment of the 25 new fabric.

Referring now to Fig. 1, the yarn 1, traversing a plurality of loops or stitches, the number of which varies with the character of the design to be produced, reaches 30 point 1' and, thereafter, itself forms a course of loops or stitches, whereas an adjacent yarn 2, forms loops or stitches to be traversed by the substantially straight portion of yarn 1, before it, at 2', itself begins 35 to form a substantially straight portion traversing the loops formed by yarn 1. Yarns 3 and 4 and any number of succeeding 40 yarns may be similarly arranged and it is obvious that a variety of designs may be produced by proper selection of the number, dimensions and color of the different 45 yarns.

The interlocking of the independent yarns is clearly shown in Fig. 2, and it will be 50 seen that at the left of the figure, the yarn 1 is located entirely behind the strands 4, 2, 2 and 4, forming the first vertical row of loops of Fig. 1, the closed portions of the loops extending upwardly. The next adjacent vertical row of loops, having the 55 closed portions of the loops extending upwardly, is traversed by yarn 1, in passing between yarns 4 and 2, so as to be located behind yarn 4, 4, but in front of yarn 2, 2.

55 The next adjacent vertical row of loops

corresponding to the first row and alternating with the adjacent rows, may appear repeatedly and in variations, and there is practically no limit to the modifications of arrangement of the yarns resulting in different designs. The change from traversing straight yarn into looping or stitching yarn is clearly shown at points 1' and 2', and it is obvious that by a proper disposition of this point of change, an additional element 60 is provided useful in the production of designs of any desired character.

The greatly enlarged representation of a number of adjacent rows of loops or stitches, shown in Fig. 3, discloses at 5, 6 and 7, three 65 rows of stitches with upwardly extending closed portions of the loops, interlocked by alternating rows of stitches with downwardly extending closed portions of the loops. The traversing, substantially straight 70 portions are shown at 8 and 9, and the bights engaging adjacent rows of stitches, at 10, 11, 12 and 13. Rear bight 10, of Fig. 3, shows the engagement by yarn 1, of the first group of strands 4, 2, 2, 4, at the extreme 75 left of Fig. 2, while front bight 13, shows the engagement of yarn 1 and the second group of strands 4, 2, 2, 4, in which the two outer strands 4, 4, are in front, and the two inner strands 2, 2, behind the traversing 80 yarn 1. The absence of floats peculiar to the arrangement of yarns according to the present invention, is of importance resulting 85 in an increased uniformity and durability of the fabric.

The above described arrangement where- 90 in the unlooped portion is interlocked in alternate rows has special advantages since the unlooped portion is interlocked between the loops of the other yarn in a maximum 95 number of positions. It has been found necessary to pass the unlooped yarn behind alternate wales in order to insure locking in the remaining wales. Thus, if the unlooped yarn in every wale were knitted be- 100 tween the loops of the other yarn, the unlooped yarn would be substantially straight between its knitted portions and, as a con- sequence, no interlocking would result, since the interlocking depends upon the zigzag 105 path given the unlooped yarn. It has, there- fore, been found impracticable to carry the unlooped yarn between the loops of the other yarn in every wale. In other words, 110 it is very essential that the interlocking be

done in alternate or every other wale rather than in any other manner. On the other hand, if an attempt is made to interlock the unlooped yarn every fourth or every 5 fifth wale, for example, passing the looped yarn behind the remaining wales, objectionable floats are formed as previously described. Even in the case where the unlooped yarn is interlocked every fourth wale, 10 the unlooped yarn being carried back of only two successive wales, the part carried back hangs away from the fabric an amount far more than would be expected from the appearance of a fabric wherein the yarn is 15 carried back of only one wale at a time as shown in the drawings illustrating this invention. The dangling yarn is, of course, highly objectionable since it is likely to be broken by being caught or snagged. Since 20 dangling portions are formed by carrying the unlooped yarn behind even only two wales at a time and since these dangling portions are entirely absent when the unlooped yarn is carried behind only one wale at a time, 25 it is, therefore, essential that the unlooped yarn be interlocked in alternate wales rather than every fourth wale or in any other manner.

What is claimed is:—

A knitted fabric comprising a plurality 30 of independent yarns making certain portions of the front of said fabric one color and other portions another color, each of said yarns in turn forming a looped portion and a transversely extending unlooped portion, the looped portion in each instance determining the color of the front of the fabric, each of said yarns in its unlooped portion being interlocked in alternate wales between the two sides of a loop in one row and the two sides of a loop in an adjacent row of yarn of the other color, each unlooped portion in the remaining wales being carried entirely behind the looped yarn so that the resulting zigzag path for the 45 unlooped portion insures positive interlocking in the said alternate wales, the unlooped portion being tightly drawn so that said unlooped yarn in its zigzag path lies close to the fabric and thereby prevents the 50 formation of floats.

In witness whereof the inventor has hereunto set his hand at Brooklyn, in the county of Kings and State of New York, this 25th day of March, 1921.

VINCENT LOMBARDI.
